UNITED STATES PATENT OFFICE.

FRANK C. ANDERSON, OF CINCINNATI, OHIO, ASSIGNOR TO THE AMERICAN VALVE
AND METER COMPANY, OF CINCINNATI, OHIO, A CORPORATION OF OHIO.

SWITCH STAND.

Application filed March 12, 1923. Serial No. 624,496.

To all whom it may concern:

Be it known that I, FRANK C. ANDERSON, a citizen of the United States, residing at Cincinnati, in the county of Hamilton and 5 State of Ohio, have invented certain new and useful Improvements in Switch Stands, of which the following is a specification.

My invention relates to ground-lever parallel-throw switch stands in general; and 10 more particularly, in certain respects, to the switch-stand disclosed and claimed in my Patent No. 1,427,082, dated August 29, 1922.

Its object is to simplify and economize in the construction of switch-stands of this 15 character. A further object is to reduce the height of the stand, not only economizing in material, but making it less of an obstruction alongside the track where the railway operatives must pass, thus contributing 20 further to their safety. Other objects will appear in the course of the ensuing description.

I attain these objects by the device illustrated, for example, in the accompanying 25 drawing, in which—

Figure 1 is a sectional plan view of the switch-stand, the section being through the casing on the plane of the line 1—1 of Fig. 2;

Fig. 2 is a sectional front elevation, the 30 partial vertical section being on the plane of the line 2—2 of Fig. 1;

Fig. 3 is a vertical front-to-rear section on the plane of the line 3—3 of Fig. 2, but 35 with the parts in mid position;

Fig. 4 is a detail perspective view of the rack;

Fig. 5 is a similar view of the intermediate crank arm;

Fig. 6 is a similar view of the switch-throwing-crank shaft;

Fig. 7 is a similar view of the switch-throwing-crank arm; and

Fig. 8 is a similar view of one of the lever rests.

The base of the stand comprises the middle part 1, feet 2 at opposite ends, bolt sockets 3, front shaft bearing 4, segmental rear extension 5 with bearing opening 6, depression 7 between the bearing 4 and opening 6, and pedestals 8 at opposite ends of this depression 7; this combination being similar to that of the previous invention above referred to. Here, however, I make use of 55 the single guide-bar 9, of circular cross-

section, with its ends in transverse openings of the pedestals 8, thus extending across the base above the rear part of the depression 7, up some distance from the top of the flat middle part 1 of the base, more similar to 60 that disclosed in my Patent No. 1,447,611, dated March 6, 1923.

The casing, like that in the previous inventions mentioned, comprises the front shaft bearing 10, rear extension with the 65 bearing opening 11 in its top, and bolt ears 12 registering with the bolt sockets 3 of the base, and being held down on the base by bolts 13 through ears on the base and casing at opposite sides of the front bearings 4 and 10, and bolts 13' in the base sockets 3 and up through the ears 12.

Also similar to those of the previously noted inventions, the handle-lever 14 has at its free end the weight-handle 15, and at 70 its other end, preferably forged integral with this lever, the crank-shaft 16, lying in the bearings 4 and 10 and extending back over the front part of the depression 7.

The handle-lever crank 17 comprises a hub 80 18 fitting on the inner end of the shaft 16 and held thereon by a key-pin 17' and a transverse pin 17'', and near its free end has the rearwardly extending crank-pin 19 on a radius with the radius of the lever 14. 85 Preferably, this pin is surrounded by a rotatable bushing 19'.

The rack or slide member 20 comprises an upright transverse middle part 21 and horizontal jaw 22 extending back from the top 90 of this middle part 21, front upright guides 23, parallel to each other at opposite edges of the middle part 21, and a lower rear horizontal jaw 24. The jaw 22 and this jaw 24 spaced down therefrom have vertically aligned holes 25 at the middle of the member 20; and extending down from the opposite ends of this lower jaw 24 are side walls 26 with their front ends joining the edges of the middle part or wall 21 and rear edges 100 of the front guides 23; these side walls 26 having openings 27 in horizontal alignment transversely of the member 20, up a short distance from the bottom thereof. The crank 17 has its pin 19 between the guides 23. 105

The target-shaft or switch-throwing-crank shaft 28 has a diametrical bore 29 receiving the intermediate-crank arm 30, which is cylindrical to fit the bore snugly but slidingly, but has its front end flat- 110

tened and widened, forming an eye 31 fitting between the top element 22 and jaw 24 of the rack 20 to turn on the intermediate-crank pin 32, which is inserted up through the openings 25 with its head 32' up against the bottom of the lower jaw 24. The horizontal guide-bar 9 is received through the horizontally alined openings 27 of the rack 20, guiding the rack rectilinearly transversely of the stand; the crank-pin 32 being hold up in its place by its head against the top of this bar 9. Preferably, the crank-pin 32 does not extend up to the top of the top element 22, but leaves a shallow recess 33 thereat, to receive and hold lubricant for the crank-pin bearing and also the guide-bar bearing, as the lubricant leaks from the crank-pin bearing. The lubricant is supplied through either one of two holes 33' in the casing top, accordingly as the parts are near one or the other end of the guide-bar 9. Similarly, the shaft 28, which has a reduced journal part 34 in the casing bearing opening 11, has a lubricant passage 35 down through the shoulder thus formed on the shaft, into the crank-arm opening 29 at the sides, one or the other registering with a single middle hole 35' in the casing in front of the bearing opening 11 as the shaft turns through 90°.

The lower end part of the shaft 28 extends down through and bears in the base bearing opening 6, with an annular flange 36 bearing in a depression 37 formed in the rear segmental part 5 of the base around this opening 6; this depression catching lubricant from the upper parts for supplying it down into the lower bearing 6.

The bottom of this part of the base has the downwardly projected hub 38 added to this bearing 6; and below this hub the shaft 28 has the diametrical threaded opening 39, into which is screwed the switch-throwing-crank arm 40, having at one end the flattened and widened eye 41 which is straddled by the members of the forked switch-connecting rod 42, part of which is shown with the pin 43 down through vertically alined openings in the fork members and through the eye opening registering therewith. This pin is kept down, in practical operation, by the bottom of the base 1 and by rear extensions 44 of the base, which have the slots 45 at opposite sides of the crank bearing through which the pin 43 may be inserted when the crank is in a mid position at either side of the bearing, accordingly as the crank connection must be made to a switch in one direction or the other, as fully disclosed and claimed in my Patent No. 1,389,730, dated September 6, 1921. The crank-arm 40 may be screwed in or out to shorten or lengthen the throw of the crank, for different switches, or to compensate for wear; and

may be removed and screwed into the shaft 28 from the opposite side, for switches connected in the opposite direction, as will be understood.

The rear part of the bottom of the depression 7 of the base 1 is higher than the front part which receives the crank 17 at either end of its throw; this part forming a table 46 from end to end of the depression, on which ride the bottoms of the front upright guides 23 of the rack member 20, so that this member substantially does not tilt on its single round guide-bar 9. This tilting also is opposed by the rather close bearing of the eye 31 between the elements 22 and 24 of the rack 20, and the snug sliding fit of the crank-arm 30, of which the eye 31 is an integral part, in the shaft opening 29. Conversely, this rack 20, held down by the bar 9, holds the shaft 28 down, by these bearings of the arm 30 and its eye 31.

The top of the shaft 28 is further reduced, above its journal part 34, forming a shank 47 over which is slipped the recessed end of the member 48, which may be a target shaft, or lamp tip, or the like, as is well known in the art, for which reason only part of this member 48 is shown. The front bearing has a bushing 49 around the handle-lever shaft 16, held by a hollow pin 50 through which lubricant is supplied, according to my Patent No. 1,427,082, first above mentioned.

To receive the handle-lever 14 at either end of its throw, the lever-rests 51 are provided, to rest on the ties or head blocks, not shown. Each lever-rest 51 has the base 52 extended back under the respective foot 2 of the base 1, in a recess 53 formed in the bottom of the front part of the foot; and this base 52 of the lever-rest has near its rear end a spike-opening 54 registering with the front spike-opening 55 of the base foot 2 and fits rather snugly in the foot recess 53 at its sides. It thus is fixed in operative position by a single spike through the registering openings 54 and 55, which is one of the six spikes usually employed to hold the stand down on its head blocks; the other spikes being driven through the rear spike-openings 56 and the end spike recess 57 of each foot 2. By thus securing the lever-rests without additional spikes, the labor of installation is lessened, and the number of openings in the wooden head blocks is reduced; which always is desirable, as each opening affords added inlet for moisture, to decay the head-block or tie.

It will be seen that the total height of the stand is much reduced, as compared with my previous inventions, and with other prior switch-stands; the intermediate-crank arm, movably connected to the direct-switch-throwing crank shaft 28 as well as to the rack 20, being down within the limits of

the upright length of the guideway for the handle-lever crank 17, instead of above that, as in my prior inventions. This permits a much smaller casing, which thus may economically be made of stronger material, as malleable iron instead of gray iron casting, permitting further reduction in bulk and weight; so that the entire construction may be made extremely light, compact and simple, yet strong and effective in operation, where a stand is required to hold without latches, avoiding the expense of those, and making the stand very convenient where the switch must be thrown frequently, as in railway yards. Its low-down construction further adds to its usefulness in such places, where the switchmen must move about in great haste, alongside the moving cars and engines, so that any undue obstruction, making them more liable to stumble, is very undesirable.

It will be understood that other forms of direct-switch-throwing crank may be substituted, such as shown in my prior patents mentioned, or otherwise known in the art, for quick adjustment or reversal, or ready repair; that shown herein merely being an example. Other modifications of the invention may occur, according to conditions encountered, and while I have shown and described specifically certain details, I do not wish to be understood as being limited thereto, but, having thus fully described my invention, what I claim as new and desire to secure by Letters Patent is:

1. In a switch-stand, mechanism comprising a lever and rack-actuating means coaxially connected, a rack engaged by said rack-actuating means, a switch-throwing crank, and an intermediate crank arm pivoted to said rack and radially slidably connected to said switch-throwing crank for rotation thereof incident to sliding of said rack.

2. In a switch-stand, mechanism comprising a lever and rack-actuating means coaxially connected, a rack engaged by said rack-actuating means, a switch-throwing crank, a shaft for said crank, and an intermediate crank arm pivoted to said rack and radially slidably engaging said shaft for rotation thereof and of said switch-throwing crank incident to sliding of said rack.

3. In a switch-stand, mechanism comprising a lever and a crank coaxially connected, a rack engaged by said crank, a switch-throwing crank, and an intermediate crank arm pivoted to said rack and radially slidably connected to said switch-throwing crank for rotation thereof incident to sliding of said rack by said lever-connected crank.

4. In a switch-stand, mechanism comprising a lever and a crank coaxially connected, a rack engaged by said crank, a switch-

throwing crank, a shaft for said switch-throwing crank, and an intermediate crank arm pivoted to said rack and slidably engaging said shaft for rotation thereof and of said switch-throwing crank incident to sliding of said rack by said lever-connected crank.

5. In a switch-stand, mechanism comprising a lever and rack-actuating means coaxially connected, a rack engaged by said actuating means, a single round guide bar on which said rack slides, means parallel with said bar on which said rack has a slideable bearing, a switch-throwing crank, and an intermediate crank arm pivoted to said rack and radially slidably connected to said switch-throwing crank for rotation thereof incident to sliding of said rack.

6. In a switch-stand, mechanism comprising a lever and a crank coaxially connected, a rack engaged by said crank, a single round guide bar on which said rack slides, means parallel with and below said bar, said rack having its part engaged by said crank extended down and slidably bearing on said parallel means, a switch-throwing crank, and an intermediate crank arm pivoted to said rack and radially slidably connected to said switch-throwing crank for rotation thereof incident to sliding of said rack by said lever-connected crank.

7. In a switch-stand, mechanism comprising a lever and a crank coaxially connected, a rack engaged by said crank, comprising upright guides receiving the engaging part of the crank, opposite transverse jaws one above the other, and side walls below said jaws, a guide bar fitting slidably through said walls, a switch-throwing crank, and an intermediate crank arm pivoted to said rack between said jaws and radially slidably connected to said switch-throwing crank for rotation thereof incident to sliding of said rack by said crank.

8. In a switch-stand, mechanism comprising a lever and a crank coaxially connected, a rack comprising upright guides between which said crank engages, opposite transverse jaws one above the other and side walls below the jaws, a single round guide bar fitting slidably through said walls, means below and parallel with said guide bar, said guides extending down and bearing on this means, a switch-throwing crank, a shaft for said crank, and an intermediate crank-arm pivoted to said rack between said jaws and slidably engaging said shaft for rotation of said shaft and switch-throwing crank incident to sliding of said rack by said lever-connected crank.

9. In a switch-stand, a lever and a crank coaxially connected, and means comprising a rack engaged by said crank, an arm pivoted to said rack, and a shaft in which said arm slides radially to rotate said shaft.

115

120

125

130

10. In a switch-stand, a base, a lever and a crank coaxially connected and mounted on said base, a rack engaged by said crank, up-standing means on said base, and a guide bar on said means, on which said rack slides, a shaft journaled in said base, and an arm sliding radially in said shaft and pivoted to said rack.
11. In a switch-stand, a rack member comprising upright guides and transverse jaws one above the other.
12. In a switch-stand, a rack member comprising upright guides, transverse jaws one above the other, and guiding bearing means below said jaws.
13. In a switch-stand, a rack member comprising upright guides, transverse jaws one above the other, and guiding bearing means below said jaws, said guides extending below said bearing means to form additional bearing means.
14. In a switch-stand, a rack member comprising upright guides for engagement of a crank, and transverse jaws one above the other, and a round arm with a flat head pivoted between said jaws.
15. In a switch-stand, a shaft having a diametral opening to slidably receive an operative connection, and a crank arm on said shaft, spaced away from said opening axially of the shaft.
16. In a switch-stand, a shaft having a diametral opening to slidably receive an operative connection, and having a threaded diametral opening to adjustably receive a second operative connection.
17. In a switch-stand, a shaft having a diametral opening to slidably receive an operative connection, and having lubricant passages leading into said opening at opposite sides thereof, and a bearing element for said shaft having a single lubricant passage

with which one or the other of said shaft passages registers as the shaft is turned one way or the other.

45

18. In a switch-stand, a rack member having transverse jaws one above the other, an element between said jaws, and a pivot pin through said element and the lower one of said jaws, and extending only partly 50 through the upper jaw, leaving a lubricant receptacle.

19. In a switch-stand, a rack member having lateral bearing means, a bar on which said bearing means bear for guiding said 55 rack, jaws on said rack, one above the other, above said bar, an element between said jaws, and a pivot pin through said element and extending through the lower jaw and into the upper jaw, said pin being held up by 60 said bar.

20. In a switch-stand, mechanism comprising a lever and a support for said lever having an opening for fastening means, and a rest for said lever extending under said 65 support and having an opening registering with the support opening for passage of a common fastening means for said support and the lever rest.

21. In a switch-stand, mechanism comprising a lever and a support for said lever having a recess in its bottom and an opening for fastening means entering from the top of the support into said recess, and a rest for said lever extending into said recess and 75 fitting along the side of the recess, having an opening registering with the support opening for passage of a common fastening means for said support and the lever rest, said lever rest being prevented from swinging laterally on said fastening means by the 80 sides of the recess.

FRANK C. ANDERSON.
